UNITED STATES PATENT OFFICE.

LEONARD O. SMITH, OF PHILADELPHIA, PENNSYLVANIA.

DESIGN FOR A BOOKLET.

SPECIFICATION forming part of Design No. 24,193, dated April 16, 1895.

Application filed October 23, 1894. Serial No. 526,771. Term of patent 7 years.

To all whom it may concern:

Be it known that I, LEONARD O. SMITH, of Philadelphia, county of Philadelphia, State of Pennsylvania, have invented and produced 5 a new and original Design for a Display-Booklet, of which the following is a full, clear, and exact specification.

My design is illustrated by the accompanying drawing in which the booklet is illustrated 10 in perspective.

The leading feature of my design consists in a card A having thereon separate vertical series of elongated perforations B B, these series of perforations being arranged side by 15 side so as to give the effect to the eye, of lines extending transversely as well as vertically

across said card. The elongated perforations are all represented as lying in parallel planes, there being four rows of said perforations, the uppermost row of transverse perforations 20 being represented as nearer the upper edge of the card than the distance represented by the lowermost row to the lower edge of the card.

Having thus described my invention, what 25 I claim is—

The design for a display booklet substantially as herein shown and described.

LEONARD O. SMITH.
